UNITED STATES PATENT OFFICE.

JOHN FRASER, OF HACKENSACK, AND THOMAS GRAY, OF PATERSON, NEW JERSEY.

MACHINE FOR EDGING METAL PLATES.

No. 910,471.

Specification of Letters Patent.

Patented Jan. 19, 1909.

Application filed July 22, 1908. Serial No. 444,858.

To all whom it may concern:

Be it known that we, JOHN FRASER, a citizen of the United States of America, residing in Hackensack, in the county of Bergen, in the State of New Jersey, and THOMAS GRAY, a subject of the King of Great Britain and Ireland, residing in Paterson, in the county of Passaic, in the State of New Jersey, have invented certain new and useful Improvements in Machines for Edging Metal Plates, of which the following is a specification.

This invention relates to a machine more particularly intended for use in the manufacture of metal pipes with rivetless longitudinal joints from metal plates, and the invention consists in an improved construction of machine for the upsetting and planing of the longitudinal edges of the plates by means of which the rivetless joints are produced.

In the accompanying drawings in which is shown a machine embodying our invention, Figure 1 is a transverse section on the line 1—1, Fig. 2; Fig. 2 is a side elevation; Fig. 3 is a longitudinal section on the line 3—3, Fig. 1; Fig. 4 is a view on a smaller scale, showing a change of adjustment; and Fig. 5 is a transverse section of a modification.

As is customary in this class of machines, the principal elements include a work table on which the plates P are clamped by means of a clamping frame and tool carrying standards on opposite sides of the work table and plate to be operated on.

While one feature of our invention herein-after described is applicable to these machines, whether the tool-carrying stands or the work table and plate constitute the traveling part of the apparatus, certain other features are applicable only to such a machine in which the work table is stationary, and in the accompanying drawings we have shown all our improvements applied to stationary work table apparatus.

Referring to Figs. 1, 2 and 3, the stationary work table A consists of longitudinal girders supported at their opposite ends only on foundations F, F¹, (Fig. 3), so that underneath there is a clear way nearly the full length of the work table or at least more than the length of the longest plate to be operated on.

As shown in Figs. 1, 2 and 3, the table girders comprise a central pair of girders or box girders 5, 5, and side girders 6, 6, united to the central girders 5, 5, by cross braces 7, 8. The side girders 6, 6, are of less height than the central girder 5, 5, so as to permit

of the mounting upon these side girders and braces 7, of laterally adjustable beams 10 and removable filler blocks 9, so that by removing filler blocks 9 of one size and replacing them by blocks of other sizes, say smaller than those shown in Fig. 1, and as shown in Fig. 4, for example, the table may be arranged for work on varying widths of plates P.

The clamping frame B, which comprises central girders 11, 11, and laterally adjustable side girders 12, 12, are secured together at their opposite ends by transverse beams 13, which in turn are supported by the stationary table A through the medium of any suitable hydraulic jacks J, by which the whole clamping frame B may be raised and lowered for the insertion, clamping and withdrawing of the plates P to be operated on, as will be readily understood.

D, D, are the two tool carrying standards on opposite sides of the work table, E being suitable tools to operate upon the edges of the plates P to plane and upset them. These standards D, D, are connected together both above and below the work table by suitable means. In the drawings I have shown threaded bars G, G¹ for the purpose, with nuts 14, permitting of lateral adjustment of the standards to operate on different widths of plates P. To permit of this, the tool-supporting part of each standard is made to project inwardly, or overhang, as shown at 15, Fig. 1, so that when the work table and clamp are adjusted for operation upon the narrower widths of plates P, the tools may be carried inwards over the non-adjustable part of the work table, as illustrated in Fig. 4. This is a matter of practical importance in machines of this character, whether the work table or the tool carrying standards be the traveling part.

In our present machine, here illustrated, the tool-carrying standards constitute the traveling carriage, and to permit of this while at the same time permitting lateral adjustment of the tool-carrying frames, we mount the foot-pieces d, d, of those standards to travel upon guideways H, H, which are laterally adjustable upon the bed plates N. These bed-plates may be made with T-head cross-slots 16 to receive T-head bolts 17 passing through the flanges of the guideways H, H, to secure the latter in any of the positions to which they may be adjusted laterally of the machines. By reason of the fact that the work table is supported at the

opposite ends, as before described, a clear way is left for the tie rods G^1 in the travel of the tool carriage.

The projecting parts 15 of the standards 5 D and the sides of the beams 10 may be provided with suitable bearing faces 26, 27, Fig. 1.

While we do not wish to restrict ourselves to any particular construction of feed mechanism for the traveling of the tool carriage, we have shown in the drawings one which is applicable. It comprises two longitudinal screw-threaded rods K each mounted in fixed bearings 18, 19 at opposite ends of the 10 machine, and threaded into suitable feed nuts 20, carried by the standard D. The feed screws may be driven by any suitable mechanism, as for example, a worm and worm wheel motion 21, Fig. 2. Between 15 each standard D and each fixed bearing 18 (19), we prefer to provide a supporting pedestal M, (M^1) resting and adapted to travel upon the guide way H. Each pedestal has secured to it a horizontal rod 22 passing 20 through a hole in a flange 24 (25) of the standard D, but each rod has an enlarged head 23 at its outer end to engage the flange 24 (25) when the travel of the standard brings its flange 24 (25) to the head. Thus 25 assuming the tool-carrying standard D in Fig. 2 to be traveling in the direction of the arrow, by the rotation of the feed screw K, the flange 24 has come into contact with the head 23 of the rod 22 and is drawing the supporting pedestal M after it, so that by the 30 time the standard has reached the end of its travel, the pedestal M will be about midway between the bearing 18 and the standard D. Meantime, the forward side of the standard 35 D has come into contact with the pedestal 19 and pushed it ahead. On the return travel of the tool carriage, the reverse action will take place, that is, the lost motion connections between the standard D and pedestals will permit both pedestals to stand still 40 for the first part of the traverse, and then the pedestal 19 will be drawn after the standard at a suitable distance to support the screw feed rod and the pedestal 18 will be pushed 45 ahead out of the way.

In Fig. 5, we have shown a slightly modified form of our machine, in which instead of having filler pieces between the beams 10 and the central girders 5, 5, we provide 50 movable filler pieces 29 bolted to the standards D, D, between the latter and the girders 6¹ of the work table. The girders 6¹ are pro-

vided with bearing faces 28. The lateral adjustment of the standards can be effected by changing the size of filler pieces 29 and 55 by laterally adjusting the beams 10 of the work table and the girders 12 of the clamping frame, as before.

We claim as our invention—

1. A machine for edging plates, having a 60 work table and clamping frame in combination with transversely adjustable standards having laterally projecting tool-carrying parts adapted to overhang the table when the standards are adjusted inwardly to work 65 on small size plates.

2. A machine for edging plates, having a work table and clamping frame, the latter and the upper part of the table being laterally adjustable for different widths of plates, 70 in combination with transversely adjustable standards having laterally projecting tool-carrying parts adapted to overhang the lower part of the table when the standards, clamping members and the upper part of 75 the table are adjusted inwardly to work on small sizes of plates.

3. A machine for edging plates, having a stationary work table and clamping frame, in combination with traveling tool-carrying 80 standards on opposite sides of the bed and means for tying together the said standards both below and above the work table.

4. A machine for edging plates, having a stationary work table and fixed supports for 85 its opposite ends, leaving a clear way underneath to near the ends of the table and a clamping frame, in combination with traveling tool-carrying standards on opposite sides of the bed and means for tying together 90 the said standards both below and above the work table.

5. A machine for edging plates, having a stationary work table and a clamping frame, in combination with tool carrying standards 100 and laterally adjustable ways extending longitudinally of the table and upon which said standards may travel, and means for tying together the said standards both below and above the work table.

In testimony whereof we have signed our names to this specification, in the presence of two subscribing witnesses.
